DRIER FOR PHOTOGRAPHIC STILLS

August E. Mutschler, Hudson Heights, N. J., assignor to Cinema Patents Company, Inc., New York, N. Y., a corporation of New York

Application July 14, 1932. Serial No. 622,407

1 Claim. (Cl. 198—134)

This invention relates to an improvement in driers for photographic stills. It may also be used for drying other objects or materials which are in the form of stiff sheets, or which may be mounted upon plates for the process of drying.

The invention consists primarily of a long horizontal cabinet through which air, which has been previously conditioned as to temperature and humidity, is circulated; and in which cabinet is an endless conveyor embodying a novel tray construction whereby photographs, mounted on ferrotypes, may be carried in oblique position to increase the effectiveness of the drying air, and contribute to economy of space.

Fig. 1 is a side view in section of the entire drier.

Fig. 2 is an end view in section taken on the line 2—2 of Fig. 1.

Fig. 3 is an enlarged fragmentary view of the conveyor which has an endless chain device and attached wire trays.

Fig. 4 is an enlarged fragmentary view of a baffle adjustment which controls the volume of air admitted at different points of the drying chamber.

Objects and advantages of the invention will be made apparent in the description of the machine.

A horizontal cabinet 1, which I preferably make of sheet metal on an angle iron frame, is supported upon a series of stanchions 2.

The cabinet is open at the feed-in 3 and at the delivery end 4. Located above the cabinet 1 is an air blower 5 of conventional design which directs conditioned air through a duct 6. This duct communicates through several openings 7 with a chamber of the cabinet 1. Exit for the air which has passed through the chamber is at 8. Due to the direction of the draft through the cabinet, some air will probably be drawn through the opening 4 from the room where the drier is located, and some air will be discharged through the opening 3; but this intake and discharge is negligible. The main circulation is from the blower 5 through the duct 6 to the chamber in the cabinet 1, and out through the lower duct 8.

The capacity of each opening 7 is separately adjustable by a baffle 10 which swings on a pivot 11, and is moved up or down to open or close the passage, by means of a handle 12 which is on the outside of the duct 6 and which may be locked in any desired position by thumb screw 13.

Arranged to travel horizontally lengthwise of the cabinet 1, is an endless carrier 15. This is made up of two chains 16 and 17, which are

identical and which travel on opposite sides of the cabinet adjacent to the inner walls thereof. The direction of this travel is indicated by the arrow 18 in Fig. 1.

Each chain is made up of links 19 and 20, alternating in the manner indicated in the drawings, Fig. 3; the links of each chain being tied by rods 21 which extend across the cabinet, and which support the wire trays 40 hereinafter referred to.

Roller bearings 22 are freely mounted on the rods 21 and serve the double purpose of separating the plates which make up the chain links, and providing a bearing surface for supporting the chain in its course of travel.

These roller bearings 22 are caught by teeth, not shown in the drawings, of conventional sprocket wheels 25 and 26 located at opposite ends of the cabinet. Between these sprocket wheels 25 and 26 the roller bearings 22 travel on horizontal tracks 27 and 28, 29 and 30, which are made up of angle irons extending longitudinally along the inner walls of the cabinet 1.

The chains 16 and 17 are moved in synchronism by two of the sprocket wheels 26, one at each side 80 of the cabinet, which are rotated by an electric motor 31 transmitting power through a Reeves-drive 32 and by which variable speed of the chains is obtained, and a gear-reduction box 33; so the chain moves through the drying chamber with relative slowness.

Immediately adjacent the sprocket wheels 26, at the delivery end of the device, is an endless belt 35, inclined between an upper roller 36, which is power driven, and a lower roller 37, 90 which merely supports the belt. The roller 36 is rotated from the same power source as the endless chain.

The trays 40 are made up of heavy wire, bent around the rods 21; and they are formed in such 95 manner that each tray has an intermediate wire portion 41, consisting of several wires arranged in a plane against which the ferrotype or other sheet may rest while in the drying chamber; these wires making up the portion 41 are 100 connected to a transverse wire 42 turned at the ends so they are parallel to the wires in the portion 41, also having an upturned section of wire at each end of the tray, providing a guard to prevent the ferrotype from sliding off at one 105 end of the tray. The wire of each tray is bent so that short ends 43 and 44 of wires 41 and 42 respectively extend from the rod 21 on which they are mounted, back to the last succeeding rod 21, on which they rest, one above and one below, 110

in such a manner that the rod may rotate between them. The two sections 43 and 44 are welded to a cross wire 45 as indicated in Fig. 3 and thus form the lower edge of the tray upon which the ferrotypes may be supported.

It is necessary to have the extreme end of the short sections 43 and 44 engage the last succeeding rod 21 freely because of the rotation occurring when the endless chain curves around the sprocket wheels 25 and 26.

Links 50 connect each of the rods 21 at the center thereof, for imparting rigidity to the structure.

For the operation of the drier, an attendant is desired at each end of the device. Prior to entering the drier, the photographs, having been taken from the wash tanks, are mounted on ferrotypes and squeegeed. In Fig. 3, the ferotype is indicated by the numeral 55 and the photograph by the numeral 56. The photograph is face down on the ferotype.

The operator at the feed-in end 3, utilizing a shelf 57 if he desires to stack the photographs, places the ferrotypes carrying the photographs on the trays one after another in the manner indicated in Figs. 1 and 3. The particular machine illustrated has two trays on each rod 21.

Air is circulated through the drying chamber as heretofore described, that is, in the direction

30

opposite to the travel of the photographs, and in so doing dries the photographs.

As the photographs reach the delivery end 4 of the drier, the trays in descending around the sprocket wheels 26 tip over so that the ferrotypes slide off the trays and on to the inclined belts 35. By these belts, the ferrotypes, carrying the photographs on their upper surfaces, are delivered to a shelf 58, where an operator strips the photographs from the ferrotypes.

Having described my invention, I claim as new and patentable:

In a drier for photographs and the like, a carrier comprising: a pair of endless chains; two pairs of sprocket wheels arranged to support and drive the chains in parallel paths; a plurality of supporting rods extending from one chain to the other and forming supports for trays; and a plurality of trays secured to the supporting rods, each of said trays comprising a wire wrapped around the supporting rod and having a short end extending back to rest on the last succeeding rod, another wire wrapped around the supporting rod and having a short end extending back to rest on the opposite face of the last succeeding rod, and said two short ends being secured in fixed relationship to each other.

AUGUST EMIL MUTSCHER.
